ELECTROLYTIC APPARATUS

Archibald J. MacDougall, Toronto, Ontario, Canada, assignor to MacDougall Chemical Company, Toronto, Ontario, Canada, a firm composed of said MacDougall, David Ross and John V. Culbert

Application December 17, 1937, Serial No. 180,265

3 Claims. (Cl. 204—5)

This invention relates to electrolytic cells adapted for the electrolysis of aqueous solutions in which process at least one of the products of decomposition is a gas, such, for example, as in the electrolysis of sodium chloride for the production of sodium hypochlorite where hydrogen is given off, and my object is to devise a simple, cheap and durable cell in which the desired reaction can be rapidly and cheaply carried out without the occurrence of undesirable secondary reactions.

I attain my objects by means of a construction which may be briefly described as follows:

A tubular upwardly extending cell wall is provided of non-conducting material such as glass. Positioned within the cell wall and substantially closely fitting the interior of the wall are a plurality of blocks of some conducting material, such as carbon, which is substantially inert in the presence of the electrolyte and the electrolytic products.

These blocks are held in spaced relationship by suitable insulating means and each has an axial opening therethrough so that electrolyte 25 may flow serially therethrough. A source of direct electric current is connected to the end blocks of the series so that the current passes through the series of blocks and through the spaces between the blocks which are filled with 30 electrolyte.

Decomposition takes place and the composition of the electrolyte must be such that at least one of the products formed is a gas. The gas is formed in small bubbles which coalesce to form 35 larger bubbles which rise through the conduit formed by the openings in the blocks and lift the electrolyte and the liquid products of decomposition to circulate them to and from a crock or container in which the cell will usually be 40 placed.

The gas bubbles not only serve to circulate the electrolyte but also interrupt, more or less, the continuity of the column of electrolyte and thus prevent current flowing directly through said 45 column from end block to end block without passing through the intermediate blocks.

The invention is hereinafter more fully described and is illustrated in the accompanying drawing in which

50 Fig. 1 is a vertical section of a single cell constructed in accordance with my invention; and

Fig. 2 a cross section on the line 2—2 in Fig. 1.

In the drawing like numerals of reference indicate corresponding parts in the different figures.

Referring to the drawing, 1 is a crock or con-

tainer preferably formed of porcelain or glass and which contains, when the device is in use, the electrolyte. Fitted within the container is a base 3 which is preferably spaced from the bottom of the container, as, for example, by resting on the ledges 2 formed adjacent to the bottom of the container. The base is preferably formed of carbon or other conducting material not affected by the electrolyte and is formed with one or more openings 3a. On this base there rests or is connected a glass tube 5 which is of some considerable length. Fitted within the tube are a series of blocks 6, 6a and 6b. These blocks closely fit the interior of the glass tube. The blocks are preferably made of carbon, though other conductive materials inert in the presence of the electrolyte might be employed. The lower block 6a is threaded or otherwise secured in the base 3. These blocks 6, 6a, 6b are held in spaced relationship so that the electrolyzing current will 10 pass from block to block through the electrolyte. I show as spacers either glass pins 7 fitted in holes in the adjacent faces of adjacent blocks or else a glass ring separator as shown at 7a. Other non-conducting materials inert in the 15 presence of the electrolyte might, of course, be employed.

The carbon blocks are preferably about $\frac{3}{4}$ " in length and 1" in diameter while the preferred spacing between the nearest portions of adjacent 20 blocks is substantially $\frac{1}{8}$ ", though these proportions 25 may be varied within reasonable limits.

The number of blocks employed will depend on the voltage of the current used. With 110 v. current about sixteen gives good results.

Through each block is formed an opening or 30 passageway 10, preferably about $\frac{1}{4}$ " in diameter. These openings or passageways form a continuous conduit through which an electrolyte may 35 flow from the bottom of the container 1 to the passageway 10 in the upper block 6b, which passageway 10 is preferably turned laterally as shown at 9.

The glass tube 5 is formed with a laterally extending spout 9a which receives the outflow 40 from the passageway 10 of the block 6b. The discharge consists of a mixture of gas and liquid which separate as soon as discharged, the liquid 45 passing into the container 1 while the gas passes off and may be collected, if desired.

The upper block 6b is formed as shown as the 50 terminal to which a lead from a source of supply of direct current may be connected.

The electrical connection with the lower block 6a may be obtained by securing a carbon rod

4 in the base 3, which rod extends up to a position above the top of the container 1.

The underside of each block 6, it will be noted, is formed with a conical concavity intended to direct bubbles of gas and upflowing liquid into the openings extending up through the blocks.

The blocks and the openings therein are so arranged and proportioned that the volume of the bubbles formed and travelling up through the openings produces an insulation in the electrolyte between the cells formed by adjacent blocks and prevents direct passage of current throughout the length of the electrolyte in the conduit formed by the openings.

15 It is found that in order to prevent heat reactions, which reduce efficiency, it is desirable to cool the tube 5 which is provided with the jacket 11 for that purpose. A cooling liquid may be circulated through the jacket by means 20 of the pipes 12 and 13 preferably to keep the temperature within the tube at or below 100° F.

The mode of operation of the cell will be evident from the above description. A direct current of electricity passes through the series of 25 blocks 6 and through the spaces between said blocks, which, of course, are filled with electrolyte and, when a solution of sodium chloride is being electrolyzed to produce sodium hypochlorite, hydrogen gas is released. Small bubbles of 30 gas formed on the surfaces of the electrode blocks or in the electrolyte are collected by the concave bottoms of the blocks and directed upwardly through the openings 10. The gas thus acts as a lift and causes a rapid circulation of the electrolyte up through the conduit formed by the 35 openings 10 and out through the passageway 10 of the uppermost block 6 and out through the spout 9 to fall into the liquid in the container.

The process is continued until the sodium chloride is substantially converted into sodium hypochlorite and hydrogen.

40 It is found in practice that the speed of the

electrolytic action is such that there is insufficient time for the setting up of undesired reversed reactions. From the speed of travel of the electrolyte it follows also that cell heating is minimized and undesired secondary heat reactions are thereby prevented or minimized.

What I claim as my invention is:

1. In an electrolytic cell the combination of an upwardly extending tube of non-conducting material; a series of blocks of conducting material inert to the electrolyte and fitting closely within the tube and held in spaced and non-conductive relationship to one another to form a series of electrolyte spaces, each block having a central opening therethrough forming the sole 15 connection between the adjacent spaces, all of the openings being substantially concentric with one another so that all the electrolyte flows through each of the spaces consecutively.

2. An electrolytic cell according to claim 1 in 20 which the lower end of each block is formed with a conical concavity forming a flaring mouth to the opening in the block.

3. In an electrolytic cell the combination of a carbon base; a carbon rod secured to and extending up from the base forming an electric terminal; a tube of non-conducting material extending up from the base; a series of blocks of conducting material inert to the electrolyte and fitting closely within the tube and held in spaced 25 and non-conductive relationship to one another to form a series of electrolyte spaces, each block having an opening therethrough forming the sole 30 connection between the adjacent spaces, all of the openings being substantially concentric with 35 one another, so that all the electrolyte flows through each of the spaces consecutively, the lowermost block being secured to and opening through the base and the uppermost block serving as an electrical terminal.

40 ARCHIBALD J. MacDOUGALL.
